Gis. E. Lenn.

Walter Farnamiss

Inventor:

Louis G. Kregel
By Knight & Dr
Atty's.

UNITED STATES PATENT OFFICE.

LOUIS G. KREGEL, OF ST. LOUIS, MISSOURI.

DESIGN FOR A COFFIN-PEDESTAL.

SPECIFICATION forming part of Design No. 21,757, dated August 2, 1892.

Application filed June 22, 1892. Serial No. 437,654. Term of patent 14 years.

To all whom it may concern:

Be it known that I, LOUIS G. KREGEL, a citizen of the United States, residing at the city of St. Louis, in the State of Missouri, have invented and produced a new and original Design for Coffin-Pedestals, of which the following is a specification, reference being had to the accompanying drawing, forming a part thereof.

10 The drawing is a perspective view of a coffin-pedestal, showing my design.

1 is an angular base, and 2 is an angular top, located in parallel planes. The body 3 of the pedestal, extending from the base to

the top, is circular or rounding in form, and tapers from the base and top toward the center, where it is surrounded by a band 4. The body has plait extending upwardly and downwardly. The parts of the base and top, which are in sight, have the same surface appearance as the body.

What I claim is—

The design for a coffin-pedestal, substantially as herein described and shown.

LOUIS G. KREGEL.
